UNITED STATES PATENT OFFICE

JULIUS J. MILLER, OF ST. JOSEPH, MICHIGAN, ASSIGNOR, BY MESNE ASSIGNMENTS,
TO WIREBOUNDS PATENTS COMPANY, OF KITTERY, MAINE, A CORPORATION OF
MAINE.

ADJUSTABLE BOX-BLANK MACHINE.

1,191,110.

Specification of Letters Patent. Patented July 11, 1916.

Application filed June 28, 1909. Serial No. 504,667.

To all whom it may concern:

Be it known that I, JULIUS J. MILLER, a citizen of the United States of America, and resident of St. Joseph, Berrien county, 5 Michigan, have invented a certain new and useful Improvement in Adjustable Box-Blank Machines, of which the following is a specification.

My invention relates to machines for 10 making wire-bound box-blanks of that kind in which each blank consists of strips of veneer which are reinforced by cleats secured to the inner surfaces thereof, and which are connected together by binding 15 wires secured to the outer surfaces thereof, whereby the different sections of the blank are reinforced and flexibly connected together, said cleats being disposed in position to be secured to the end walls of the box.

20 My invention is applicable to machines of different kinds. I have illustrated my invention in connection with a machine of the general character shown in United States Patent No. 815,197 issued March 13, 1906, 25 and in United States Patent No. 864,955, issued September 3, 1907.

The object of my invention is the provision of improved means for quickly and effectively varying the distance between the 30 blocks or other devices for spacing the cleats apart on the work-holder of a machine for making blanks of this character. As herein disclosed, I provide means for permitting a sliding adjustment of the said spacing 35 blocks along the links of the chains constituting the traveling work-holder, or along the channels or pockets carried by said chains, whereby the said work-holder may be used with cleats of different lengths, without 40 the necessity of loosening any of the parts of the chain, or of the pockets or channels carried thereby, and whereby the machine may be readily and quickly adjusted for the manufacture of box blanks of different 45 sizes.

As will hereinafter more fully appear, I provide each spacing block with a screw, and with means operated by said screw for engaging the sides of the pockets or channels in which the blocks are held, whereby the manipulation of the screws is the only thing necessary when it is desired to vary the distance between the said blocks.

50 My invention is in the nature of an improvement on the devices disclosed in the

application of William P. Healy, Serial No. 503,116, filed June 19, 1909.

In the accompanying drawings—Figure 1 is a perspective of a portion of a chain having spacing blocks involving the principles 60 of my invention. Fig. 2 is a perspective of one of said spacing blocks. Fig. 3 is a perspective of one of the screws with which each block is provided. Fig. 4 is a perspective of one of the devices operated by said 65 screws. Fig. 5 is a side elevation of one of the links of said chain. Fig. 6 is a plan of the same. Fig. 7 is a section on line 7—7 in Fig. 5. Fig. 8 is a section on line 8—8 in Fig. 7.

As thus illustrated, the endless link belt or chain A is of the character shown and described in the aforementioned prior patents. The said chain is composed of links provided with pockets or channels B and 70 held together by bolts C, in the well known manner. Each pocket is provided with a spacing block D of the usual or any suitable form. Each block is provided with a vertically disposed screw d having a tapered 75 lower end. The tapered lower end of each screw engages the beveled inner end of two oppositely and horizontally disposed retaining devices d', which latter project from opposite sides of the block. These retaining 80 devices are adapted to engage or impinge upon the inner sides of the pockets or channels B, in the manner shown in Fig. 7. It will be seen that one of these devices d', of each block, engages in a groove b in the side 85 wall of the pocket. When the screws are tightened up the devices d' are forced apart and the blocks are then held in position in the pockets. By slightly loosening said 90 screws the blocks can be given a sliding adjustment along the pockets, thus varying the distance between them. In this way the work-holder can be adjusted or changed quickly for different lengths of cleats. If 95 long cleats are to be used, then the blocks are moved apart; but if short cleats are to be used, then the blocks are moved nearer together. In doing this it is not necessary to loosen the bolts C, as was necessary in said prior patents.

100 It follows, therefore, that the blocks are not clamped tightly by the plates of the chain, being free from clamping pressure in this respect. Thus the alteration of the chain work-holder is accomplished quickly 110

and easily and with but very little labor. Box-blanks of different sizes can thereby be made on one and the same machine without loss of time in changing from one size to another.

For the broader purposes of my invention, I do not limit myself to any particular kind of work-holder, although I prefer an endless chain work-holder.

10 By leaving off one of the retaining devices d' , preferably the one next to the chain, the entire inner face of the block will then bear against the side of the pocket, thereby producing frictional contact for 15 holding the spacing block in place. This, of course, will leave one retaining device d' in engagement with the groove b at the other side of the pocket.

I do not limit myself to the exact construction shown and described.

What I claim as my invention is:—

1. In a box blank machine, means for making blanks of different sizes, comprising a work-holder having a cleat channel, 25 spacing blocks therefor, adjustable along the length thereof, and free of clamping pressure thereby, and means including a vertical screw in each block for holding the same in different positions on said work-holder, said 30 work-holder having a longitudinal groove for engaging said means, the said blocks and means being entirely within the cleat channel of said work-holder, and each block being formed to engage the opposing ends 35 of two adjacent cleats.

2. In a box blank machine, means for making blanks of different sizes, comprising a work-holder having a cleat channel, spacing blocks therefor, adjustable along the 40 length thereof, and free of clamping pressure thereby, a screw in each block, and means carried by the blocks and actuated by the lower ends of said screws for holding the blocks in different positions on said 45 work-holder, said work-holder having a longitudinal groove for engaging said means,

the said blocks and means being entirely within the cleat channel of said work-holder, and each block being formed to engage the opposing ends of two adjacent cleats.

3. In a box blank machine, means for making blanks of different sizes, comprising a work-holder having a cleat channel, spacing blocks therefor, adjustable along the 55 length thereof, a screw for each block, a grooved support for said blocks, and means carried by the blocks and actuated by said screws for engaging the groove of said support to hold the blocks in different positions 60 on said work-holder, the said blocks and means being entirely within the cleat channel of said work-holder, and each block being formed to engage the opposing ends of two adjacent cleats.

4. In a box blank machine of the kind disclosed, a traveling work-holder having a cleat channel having a plurality of spacing blocks for spacing the cleats apart endwise in the direction of travel thereof, means on 70 the work-holder for engaging one side of each spacing block, a vertical screw in each spacing block, a retaining member carried by and projecting from the other side of each spacing block, adapted to be operated 75 by said screws, and means on said work-holder for engaging said retaining members, whereby the distance between the spacing blocks may be varied at will, all within the cleat channel of said work-holder, and 80 means for stapling the blanks as they move along, each block being formed to engage the opposing ends of two adjacent cleats, and said blocks being free of clamping pressure except by said work-holder.

Signed by me at St. Joseph, Michigan, this 21st day of June, 1909.

JULIUS J. MILLER.
